UNITED STATES PATENT OFFICE.

ANDREW B. FOANS, OF NEW YORK, N. Y.

FOOTBALL-PLAYING DEVICE.

Application filed December 8, 1926. Serial No. 153,224.

This invention relates essentially to a device for playing foot ball in which a spring propelled foot of a figure representing a person is actuated to kick a ball seated in the 5 path of the foot.

The invention is designed to provide means to retrograde the foot after it has struck the ball to its operative position, and automatic means for moving the retrograding means out of action.

The fundamental object of the invention is to provide manually operative means within the reach of the operator for moving one or any number of the legs backward to its 15 kicking position.

The invention resides more particularly in the novel combinations hereinafter described and claimed, reference being made to the accompanying drawing in which:—

20 Fig. 1 represents a side elevation of a device embodying this invention.

Fig. 2 is a rear elevation of the same.

Fig. 3 is a section taken along the line 3—3 of Fig. 1.

25 In the drawing the numeral 5 designates a base or platform having fixed thereon one or any number of figures 6 representing players in the game. One of the legs 7 of each figure is loosely arranged on a bolt 8 so that it can swing to and fro and a spring 9 mounted on the bolt propels the leg forward to kick a ball 10, as indicated in dotted lines in Fig. 1. The leg is held in its retracted position by means of a spring bolt 30 or latch 11 slidably arranged in a casing 12 secured to the base.

The bolt is normally in engagement with a projection or pin 14 on the heel of the leg so as to lock it in its backward position.

40 The bolt can be actuated by a flexible connection within reach of the operator, or as shown in Fig. 1 by means of an electro-magnet 15 connected by wires 16 to a push-button 17 within reach of the operator. Wires 18 connect the button to a battery or other source of electricity and when the magnet is energized by pushing the button the bolt is drawn toward the magnet thereby releasing the leg which swings forward by the action 45 of the spring to forcibly strike the ball.

The ball after it is kicked can be caught by a player and then thrown into a cage 19 secured to the figure. The cage has an open bottom so that the ball will drop into a shallow cup 20 secured to the base and having an opening 21 in its rear side for the foot

to pass through. The cup can be provided with a cushion to obviate rebound of the ball.

The devices for retrograding the leg after it impinges on the ball include, a link 22 having one end pivoted to the leg while the other end is provided with a hook 24, the object of which will be hereinafter described. At the rear of the figure is located 55 a pair of standards 25 having a transverse shaft 26 journaled in the standards. A crank lever 27 has its upper end fixed to the shaft and it is equipped with a pin 28 projecting from its other end. A spring 29 60 normally holds the crank lever out of engagement with the hook 24 at the end of the link.

At the forward portion of the base is secured a standard 30 having a bolt or shaft 75 31 fixed thereto and on the bolt is mounted a hand lever 32. The lever is connected by means of a rope 33 or otherwise to an opposite arm 34 extending upward from and fixed to the rear shaft. 80

When the leg is unlocked by pulling the latch backward the leg in swinging forward moves the link and the bottom portion thereof slides or rides on the pin 28 until the hook comes into engagement with the pin. 85 The leg can then be drawn backward by operating the lever 32 thereby transmitting motion to arm 34, crank lever 27 and pulling the link backward. After the link is pulled backward and the hand lever released 90 the spring 29 expands so that the pin 28 will move out of engagement with the hook and at the same time restore the hand lever to its normal position. As shown in the drawing, there are three figures in a row 95 on the base, but it will be seen that one or any number of the figures could be employed each having a crank lever and link connection with a leg of the respective figure and one lever 32 connected to one arm 34 will 100 operate one or any number of the legs. In this device when a leg is unlocked it swings forward independently of the other legs and the link connected to said leg moves to engage the pin without interfering with the 105 other links pivoted to the locked legs.

I claim:—

1. In a foot ball playing device the combination with a figure representing a player having a spring propelled swinging leg 110 adapted to kick a ball, means for locking the leg in its retrograde position, and means

including a link pivoted to a leg controlled by the operator coacting with the propelling means normally out of action when the leg is locked brought into action when the leg is unlocked for moving the leg backward after it has struck the ball.

2. In a foot ball playing device the combination with a plurality of figures representing players each having a swinging leg adapted to kick a ball, means for locking each leg in its retrograde position, and means including a link pivoted to each leg normally out of action when a leg is locked brought into action by unlocking any of the legs for moving the leg backward after it has impinged on the ball without moving the locked legs.

3. In a foot ball playing device the combination with a figure representing a player having a spring propelled swinging leg adapted to kick a ball, means for locking the leg in its retrograde position, a link having one end pivoted to the leg, a spring crank lever coacting with the other end of the link normally out of action with the link, and a hand lever connected to the crank lever for actuating the link to retrograde the leg after it has struck the ball.

4. In a foot ball playing device the combination with a figure representing a player having a spring propelled swinging leg adapted to kick a ball, means for locking the leg in its retrograde position, a link having one end pivoted to the leg, a spring

crank lever having a pin to coact with the other end of the link normally out of action, and a hand lever having a flexible connection with the crank lever for actuating the link to retrograde the leg after it has struck the ball.

5. In a foot ball playing device the combination with a figure representing a player having a spring propelled swinging leg adapted to kick a ball, means for locking the leg in its retrograde position, a link having one end pivoted to the leg, a spring crank lever coacting with the other end of the link normally out of action, an arm connected to the crank lever, and a hand lever having a flexible connection with the arm for actuating the link to retrograde the leg after it has struck the ball.

6. In a foot ball playing device the combination with a figure representing a player having a spring propelled swinging leg adapted to kick a ball, means for locking the leg in its retrograde position, a link having one end pivoted to the leg and a hook at the other end, a spring crank lever having a pin to at times engage the hook but normally out of action, an arm connected to the crank lever, and a hand lever having a flexible connection with the arm to move the leg backward after it has struck the ball.

In testimony whereof I have hereunto set my hand.

ANDREW B. FOANS.
